Specification for Design.

Patented Nov. 15, 1921.

Application filed August 26, 1920. Serial No. 406,242. Term of patent 7 years.

To all whom it may concern:

Be it known that I, HARRY L. BEACH, a citizen of the United States, residing at Coshocton, in the county of Coshocton and State of Ohio, have invented a new, original, and ornamental Design for a Display- Stand, of which the following is a specification, reference being had to the accompanying drawing forming part hereof.

The figure is a perspective view of a display stand, showing my new design.

I claim:—

The ornamental design for a display stand, substantially as shown.

In testimony that I claim the foregoing as my own, I have hereto affixed my signature.

HARRY L. BEACH.
